UNITED STATES PATENT OFFICE.

GEORGE GERSTENSLAGER, OF WOOSTER, OHIO.

ROAD-CART.

1,110,681.

Specification of Letters Patent. Patented Sept. 15, 1914.

Application filed February 20, 1913. Serial No. 749,722.

To all whom it may concern:

Be it known that I, GEORGE GERSTENSLAGER, a citizen of the United States, residing at Wooster, in the county of Wayne and State of Ohio, have invented a new and useful Road-Cart, of which the following is a specification.

My invention relates to improvements in road carts, and particularly to such as are used for driving and horse-training purposes.

Its object is to provide means for increasing the carrying capacity of such carts and improve their utility for horse training purposes.

It consists, primarily, of a novel platform or basket attachment, suspended from the rear of the cart, and means for reinforcing the supporting members of the cart adapted to the purpose, and means for detachably securing said platform thereto—all as hereinafter fully set forth, and stated in the appended claims.

My invention is illustrated by the accompanying drawings, in which similar letters and figures of reference indicate like parts.

Referring to the drawings, Figure 1 is a view in perspective of a cart embodying my invention, one wheel thereof being removed for better illustration of the parts referred to. Fig. 2 is a view of my detachable platform removed from the cart. Fig. 3 is a detail view showing the connecting or coupling means I use to secure the platform to the cart. Fig. 4 is a detail view of one of my spring-bars in connection with the thill and cross-bar, detached. Fig. 5 is an enlarged view of Fig. 4 on the line X—Y thereof, the thill and spring-bar being shown in cross section thereof.

Its construction and operation will now be set forth in connection with the letters and figures of the drawing.

Referring thereto, B shows one of the wheels and C the thills mounted on the axle, and D the seat of the cart, and E its body and front platform, all of which are quite similar to those in carts heretofore used.

1 is one of a pair of spring-bars on which 50 the seat D is mounted; its forward end is secured underneath the thill C by a clip 1^a, and the rear end thereof engages the outer edge of the seat D by a hook 16, as shown in Fig. 1.

55 The seat D is supported upon the outer ends of said pair of spring-bars, in the

usual well known way, and the platform is detachably secured to and suspended from said seat and front platform, as hereinafter described. To provide supporting means for this unusual stress upon said spring-bars 60 I reinforce the connection between the thills C and the cross bar 2 at the fulcrum point of the spring-bar 1, as illustrated in Fig. 4. For this purpose I connect the cross bar 2 65 to the thills C, respectively, without the use of mortises as heretofore which weaken the supporting strength of the thills, the ends of said cross-bar being abutted against the sides of the thills respectively, with a projecting portion over-lapping the same, as shown in Fig. 5. To further strengthen this connection for the purpose aforesaid, a metal strap 3 overlaps the extended end of 70 said cross-bar 2 and secures it to the thill by 75 extending over and around the outside thereof, and downwardly so as to engage an extension from an under clip 4 by its threaded end and nut 3^a thereon. Said under clip 80 is made of one piece of strap metal bent and fitted to lie snug against said spring-bar as a fulcrum therefor and engaging three sides thereof; from thence it extends inwardly and upwardly through a metal plate 13 lying horizontally above the spring-bar and 85 underneath said thill, and passes through the cross-bar 2 so as to engage the inner end of said strap 3, and be secured thereto by the nut 4^a, as shown in Fig. 5. The outer 90 ends of the cross-bar 2 may be further secured by means of a threaded bolt 14 driven through the strap 3 and diagonally into the thill as shown. Said seat supporting and 95 reinforcing means are, by a division, reserved for a separate application.

The detachable platform or basket P is preferably made up of a series of slats secured parallel to each other upon a pair of metal straps, bent for the purpose substantially as shown in Fig. 2. Their front or inner portions 77 are extended upwardly and terminate in hooks, each of which is adapted to engage a corresponding clip 9 attached to the front platform E at a point near the axle of the cart, and at the bends of the 105 front platform supporting members d—d respectively; said hooks engage the clips 9 in such a manner as to secure said rear platform thereto when the outer portion thereof is in elevated position, and are detachable 110 therefrom when said outer end is lowered. The outer portions 6—6 of said straps are

bent upwardly and inwardly, each terminating with a hook 10 adapted to engage a corresponding clip 17 under the seat D at the outer ends of said spring-bars 1-1; said 5 hooks are detachably secured in said clips 17, respectively, by means of a spring lever 5 which is fastened at one end underneath the seat D and extends outwardly through said clip and bears upon the adjacent hook 10 in such a manner as to prevent its escape 10 from said clip except by lifting said spring lever which extends outwardly to provide a handle therefor, as shown in Fig. 3.

The connecting mechanism for the rear 15 platform is such that when the inner ends of the straps 7 are introduced into the clips 9 when the platform is lowered at its outer end, they become secured therein by the elevation of the same to normal position shown 20 in Fig. 1; and the outer ends of said straps 6 are then entered into the clips 17, respectively, and are therein secured and held in position by the pressure of said spring-lever 5 upon the hooks 10, as aforesaid, thereby 25 making the entire platform P easily detachable. By these means also said platform may be detached by the driver whether seated on the seat D or standing upright on said platform, or from a position on the ground 30 at the rear of the cart.

The several parts may, of course be modified within the scope of my invention.

Having thus fully described my invention, what I claim is—

35 1. In a horse cart, in combination with the seat and front platform thereof, a de-

tachable rear platform having a pair of supporting arms at each end thereof; hooks on said arms, respectively; a pair of clips adapted to detachably secure the hooks of one pair of said supporting arms to said front platform; a pair of clips adapted to detachably secure the hooks of the other pair of said supporting arms to said seat, and means for disengaging said hooks from 45 said clips, substantially as set forth.

2. In a horse cart, in combination with the seat and the front platform thereof, a detachable rear platform having a pair of upwardly extended arms at each end thereof, 50 hooks on said arms, respectively; a pair of clips secured to said front platform and adapted to admit a corresponding pair of hooks projected from the inner end of said rear platform when the latter is lowered outwardly, and to secure said hooks in said clips when elevated outwardly; a pair of clips secured to said seat and adapted to admit a corresponding pair of hooks projected from the outer end of said rear platform 55 when the latter is elevated to normal position; and a manually operable spring lever extended through said seat clips, respectively, to engage said hooks therein, substantially as set forth and for the purpose 60 specified.

In witness whereof, I hereunto set my hand this 8th day of January, A. D. 1913.

GEORGE GERSTENSLAGER.

In presence of—

J. E. APPLEBAUGH,
HIRAM B. SWARTZ.
